[57] CLAIM

The ornamental design for a pendant control station, as shown.

DESCRIPTION

FIG. 1 is a perspective view of a pendant control station showing our new design;

FIG. 2 is a top plan view thereof;

FIG. 3 is a left side elevational view thereof, the other side being a mirror image;

FIG. 4 is a bottom plan view thereof; and

FIG. 5 is an end elevational view thereof.
The broken-away disclosure of the cord in FIGS. 1—4 is to show indeterminate length.
